SCUTCHING APPARATUS

Dwight E. U'Ren, Beaver Dam, Wis.

Application November 18, 1947, Serial No. 786,684

5 Claims. (Cl. 19—12)

1

This invention relates to improvements in scutching apparatus for decorticating such fibrous stems as those of hemp, flax, jute, sisal, ramie, etc.

It is the object of the invention to provide simple and effective means for decorticating the fibers while the fibers are largely air borne, the manipulation of the fibers by the air currents being an important part of the operation, and the entire process being conducted so gently and at such low speed as to leave a maximum of line fiber and a minimum of the short or snarled tow.

It is my further object to provide an arrangement in which the hurds are cleaned from the fiber both from the top and bottom sides thereof and from end to end of the fiber, the grasp of the machine on the fiber being shifted midway through the machine so that the portions of the fiber originally held are later exposed for the combing action.

More specifically, it is an object of the present invention to comb out the fiber starting with a zone at the extreme ends of a given bundle of fibers and progressively extending the length of each outward combing stroke to elongate the working zone toward the longitudinal center of the bundle, brushing and smoothing the fiber rather than cutting and tearing it and leaving the fiber in a parallel form which can be used to better advantage.

While each combing stroke is outward in direction, it is important that the combing operations commence at or near the ends of the fibers and are expanded inwardly with gradually increasing length of stroke until the entire length of the fiber is combed from the immediate proximity of the point at which it is grasped. After the fiber is brushed and smoothed and straightened progressively from one end toward the midpoint at which it is grasped, the machine automatically grasps a portion of the fiber which has already been fully combed and cleaned and the machine commences from the opposite end of the fibers to comb them, progressively enlarging the combing operation, until portions of the fibers originally held are combed. Since the long fiber or line is valuable, whereas the tangled and snarled short fiber or tow has relatively little value, it is important that my improved apparatus produces a much higher percentage of line than any decorticating apparatus heretofore known, while at the same time leaving the line cleaner and softer.

Other objects of the invention and details of

2

the apparatus in which the invention is embodied will be apparent from the following disclosure.

In the drawings:

Fig. 1 is a view partially in longitudinal section and partially in side elevation showing apparatus embodying my invention.

Fig. 2 is an enlarged detail view in cross section taken on the line 2—2 of Fig. 1.

Fig. 3 is an enlarged detail view taken in horizontal section through the apparatus, most of the apparatus being shown in plan but the top chains being omitted.

Fig. 4 is a detail view taken in transverse section on the line 4—4 of Fig. 3.

Fig. 5 is a fragmentary detail view in perspective showing the interleaved decorticating rotors, portions of the housing and conveyor mechanism being shown in section.

Fig. 6 is a greatly enlarged detail view in cross section through a portion of one of the conveyors.

Fig. 7 is a similarly enlarged view in longitudinal section through one of the conveyors.

Fig. 8 is an enlarged fragmentary detail view in perspective showing one of the rotor vanes.

Fig. 9 is an enlarged detail view in perspective showing a slightly modified form of rotor vane.

The frame 10 supports a first pair of decorticating rotors 11, 12 each provided with its own shafts 13, 14, respectively. These shafts are driven by chains 15, 16 from jack shafts 17, 18 as shown in Figs. 2 and 3 and the shafts are connected by meshing gears 19, 20 to rotate in unison.

Rotor 12 is provided with vanes 21 which may conveniently be three in number. These vanes project in a generally radial direction and may be reenforced on their rear faces by angles 22, 23 (Figs. 5 and 8). Marginally, they may be finished with combing blades 25, the exposed free margins of which are preferably rounded as shown at 26 in Fig. 8. The radial projection of the blades is progressively reduced toward the end of the rotor first encountered by the fiber in order that the initial brushing or combing action of the blades will be limited to the outer ends of the fiber, the combing action gradually being extended until the entire exposed length of each fiber is being acted upon.

Rotor 11 has vanes 210 substantially identical with those already described and provided with similar reenforcement at 22 and similar combing blades at 25. In addition, one of the vanes of one of the rotors, preferably the vane 211 of rotor 11, has comb teeth 26 which project radially from each margin as best shown in Figs. 5 and

9. The margin may have its rear face reenforced by an angle 23 as already described. Immediately within the reinforcement the vane has apertures 27 within which the angular ends of the comb teeth 26 are held. Spacers 28 between the comb teeth hold the teeth in the proper position and the teeth are fixed between the spacers by the cover plate 29, from which the points of the free ends of the respective teeth project. The cover plate is screwed at intervals to the vane 21. It will, of course, be understood that a greater or lesser number of vanes may be mounted on the rotors and more of them, if desired, may be equipped with comb teeth. The arrangement shown and described has, however, proved very successful in practice.

The spacing between shafts 13 and 14 is so determined with reference to the length of the vanes 21, 210 and 211 that as the rotors are actuated, each vane in turn just clears the opposing rotor. The vanes are preferably not exactly radial, but given a slight forward pitch as shown in Fig. 2. The driving chains for the respective rotors are so adjusted that the vanes are interleaved, each vane of one rotor passing midway between the vanes of the opposite rotor.

Rotor 11 is materially higher than rotor 12 and offset laterally therefrom. Almost directly above the shaft 14 of rotor 12 is the conveyor guide 30 at a level approximately the same as the level of shaft 13. There is just clearance for the vanes of rotor 12 to pass beneath the conveyor guide and for the vanes of rotor 11 to pass downwardly beside it. Above conveyor guide 30 is an opposed conveyor guide 31 and confined between the guides 30 and 31 are the supporting conveyor 32 and the clamping conveyor 33 between which are held the fibers 35 to be decorticated. The conveyors are shown in detail in Figs. 6 and 7 but, being generally conventional, need not be described specifically except to refer to the fact that the clamping conveyor comprises a series of clamping shoes 36 mounted on levers 37 which have rollers 38 operating on the guide 31. The clamping pressure is afforded by compression springs 39 acting individually between the respective shoes and the respective levers.

The guide 30 for the transporting conveyor is desirably extended at each side of frame 10 upon arms 40, 41 as best shown in Fig. 1. The transporting conveyor 32 comprises a chain guided around sprockets 43, 44 at the ends of arms 40 and 41 and also guided by sprockets 45, 46 at the bottom of the frame. Sprocket 46 may be a source of power communicated thereto by a driving chain 47.

The clamping conveyor 33 passes around guide sprockets 48, 49, the latter of which may be the source of power communicated thereto by chain 50.

Connected to the conveyor guide 30 and extending arcuately and downwardly therefrom about the path of the vanes 21 of rotor 12 is a semi-cylindrical housing 51 upon which rests that portion 350 of the fiber 35 which is not initially being acted upon by the decorticating and combing blades (see Figs. 3 and 4).

Frame 100 is disposed beyond frame 10, as best shown in Figs. 1 and 3. In this it mounts another pair of rotors 11 and 12, identical with those already described, except that their relative positions are reversed, as shown in Fig. 2. Above the rotor 12, now located at the left as viewed in Fig. 2, runs the supporting conveyor 320. Above this is the clamping conveyor 330. 75

Conveyor 320 laps conveyor 32 as best shown in Fig. 3, being laterally offset therefrom toward the side at which rotor 11 is located in frame 10, this being the side of conveyor 32 on which the fibers have been combed and brushed.

Between the two frames 10 and 100, the housing 51 which has extended through frame 10 about the rotor 12 gradually runs out and, just beyond the end of supporting conveyor 32, this 10 housing becomes approximately vertical at 510, where its upper margin is carried over and connected with the conveyor guide 300 of conveyor 320. Meantime, from a substantially vertical 15 beginning at 511 in connection with conveyor 15 guide 30 of conveyor 32, the housing 512 which passes through frame 100 gradually assumes its full rounded form about the rotor 12 in frame 100, as best shown in Figs. 2, 3 and 4. At the delivery end of the device, housing 512 again 20 runs out at 513 and tapers downwardly and centrally to a delivery rack 514 which comprises an extension beyond the end of conveyor 320 (Figs. 1 and 3).

For such short-stemmed plants as flax and 25 ramie, the proportions of the machine would be relatively small. For tall growing plants, such as sisal and jute, all of the dimensions would have to be correspondingly large. In an intermediate size, the machine is used for hemp.

It will be understood that the stalks of the plant are retted in the usual manner to enable bacterial action to rot away the plant cells which connect the fiber. The previously retted fiber 35 is thrown across the line chain 32 where such 35 chain is exposed at the lefthand or input end of the machine, as viewed in Figs. 1 and 3. Before it enters the frame 10, the fiber is clamped by the clamping conveyor 33 to the line chain 32 at a point approximately midway between its ends. The projecting end portions 350 of the fiber ride onto the exterior of the housing 51 where they are supported free of contact with the underlying rotor 12. The projecting end portions 351 of the fiber are subjected progressively to longer and longer strokes of the combing and brushing blades of the respective rotors and to the turbulent air currents produced by the interleaved blades which throw the fibers first downwardly and then upwardly in the manner indicated by the full and dotted lines of Fig. 2 (Fig. 2, however, relating more particularly to the operations conducted in frame 100).

It will be observed that the blades of both rotors move outwardly along the fibers toward the free ends thereof. Each blade 25 at the end of a vane of rotor 12 will brush the under surfaces of the fibers in an upward direction, while each blade 25 or comb tooth 26 of the upper rotor 11 will brush the upper surfaces of the respective fibers downwardly and outwardly. In addition, there will be blasts of air moving ahead of each of the vanes which will keep the fibers in motion and assist in the loosening of the haulds.

Whereas the ordinary decorticating machine has rapidly rotating cylinders which must be operated at a high rate of speed and usually brush only the top side of the fiber, the present rotors or cylinders travel at a slow speed combing and brushing both sides of the line fiber starting near the ends of the line and progressively increasing the stroke until the stroke commences near the middle of the line, the increase being due to the conical overall form of the respective cylinders.

If the combing action were to start immediately

near the center of the line, any snarl would necessarily involve tearing out large portions of the line which would thereupon be useful only as tow and would lose much of their value. By starting the combing action near the ends of the line, the snarls are gradually worked out and the line is straightened and softened with a minimum loss in the way of tow.

After one end of the bundle of fibers has been combed out in the manner above described, the line chain 32 laps the beginning of line chain 320 and as the bundle of fibers is clamped to chain 320, it is released from chain 32. The previously combed end portion 351 of the fiber now lies over housing 512 while the uncombed ends of the fibers are exposed to the cylinders 11 and 12 of frame 100. Due to the change of the point at which the line is held, the portions thereof originally clamped against chain 32 are now exposed for brushing and combing action. Thus the entire length of the fiber is uniformly softened, cleaned and straightened.

The housings 51 and 512 which support that portion of the line fiber not being acted upon by the cylinders are also of advantage in confining the air ahead of the respective blades of the cylinders 12, thus tending to make the line fibers float upwardly on the air currents ahead of the vanes, working the fibers and softening the action of the blades by pneumatically supporting the fibers during initial blade engagement therewith.

I claim:

1. A scutching machine comprising two line chains laterally offset, the delivery end of the first line chain laps the receiving end of the second line chain, means for actuating said chains, a scutching cylinder having its axis substantially directly beneath each such chain and provided with scutching means projecting laterally at both sides of the chain, housings at opposite sides of the respective chains extending oppositely about the respective cylinders aforesaid to cover each such cylinder at one side of its respective chain, leaving the other side of such cylinder exposed, the said housings having a unitary oblique housing connection which extends at substantially the full width of the respective housings in plan diagonally from one of said housings to the other, smoothly merging therewith, a second scutching cylinder laterally adjacent each chain, the respective cylinders associated with the respective chains having interleaved blades, means for driving the respective cylinders in a direction such that the respective vanes move outwardly from the respective chains, the line supported on the first chain being delivered to the second chain, and the engagement of the second chain therewith being offset from the point of engagement of the first chain therewith, whereby portions of such line not reached by the cylinders associated with the first chain will be scutched by the cylinders associated with the second chain.

2. A scutching machine comprising a pair of laterally offset line chains, the delivery end of the first line chain laps the receiving end of the second line chain, means for operating the respective chains for delivery of line from the first chain to the second, a pair of scutching cylinders associated with each chain, there being one scutching cylinder substantially axially directly beneath each of the respective chains and provided with scutching means projecting laterally at both sides of the chain, and another scutching

cylinder disposed beside each of the respective chains with its axis substantially horizontally offset from the chain, the said scutching cylinders of each pair having interleaved radially projecting vanes most of which have smooth finish brushing blades and others of which have marginally projectioning combs, housings at opposite sides of respective line chains about the scutching cylinders therebeneath for confining the air about the vanes of such cylinders and supporting portions of the line not acted upon by the cylinders of the respective pairs, the said housings having a unitary connecting portion merging smoothly with the respective housings and extending obliquely beneath the line chains at the time of line transfer from one of said chains to the other, the cylinder vanes being adapted to propel air currents for pneumatically floating the line pending the action of the vanes thereon and the transfer of the line from the first chain to the second chain and thereby exposing portions of the line held by the first chain to the scutching action of the cylinders of the second chain.

3. The combination set forth in claim 2 in which the respective vanes of the several cylinders have initially short radius where first engaged with the line and progressively increasing in radius rectilinearly in the direction of line movement on the respective chains whereby the scutching action commences near the outer ends of the line and progressively increases in stroke to include substantially all portions of the line depending from the respective chains, said progressive increase of vane radius having axial extent of approximately one-half the length of the cylinders whereafter the vane is substantially parallel to the cylinder axis.

4. Scutching apparatus comprising the combination with a line chain, of first and second cylinders having interleaved scutching vanes positioned to act alternately upon fibers supported from the line chain, the first cylinder being mounted for rotation upon an axis nearly centered beneath the line chain, whereby its said vanes project laterally at both sides of the chain and pass therebeneath in the rotation of said cylinder, the second cylinder being rotatably mounted upon an axis horizontally offset from the line chain and at nearly the same level as the line chain, its vanes passing downwardly in immediate proximity to the line chain, a housing projecting laterally and downwardly from the line chain and arcuately encircling that portion of the path of travel of the vanes of the cylinder beneath the line chain in which such vanes are ascending toward the line chain at the side thereof opposite the second mentioned cylinder, the fibers supported by the line chain being fully exposed at the opposite side of the line chain to the scutching vanes of both cylinders as such vanes act alternately thereon, all of said vanes having relatively short radius at the ends of the cylinders at which such vanes are first encountered by fibers supported from the line chain and having relatively greater radius at the ends of the cylinders toward which said line chain moves such fibers, whereby the action of the vanes on the fibers commences near the outer end thereof and increases until it commences in close proximity to the line chain.

5. The device of claim 4 in further combination with a third scutching cylinder mounted beyond the first and second scutching cylinders and having radially projecting scutching vanes,

7
and a line chain beneath which the axis of said third cylinder is nearly centered and which laterally laps the first line chain to receive fibers from the line chain first mentioned, a fourth scutching cylinder having vanes interleaved with those of the third cylinder and mounted for rotation upon an axis laterally offset from said second line chain and at substantially the level thereof, and a housing element extending about the path of upward movement of the vanes of the third scutching cylinder at the side of the second line chain opposite the position of the fourth scutching cylinder, and an interconnecting housing element having surfaces extending diagonally from the first mentioned housing to the last mentioned housing element, its surfaces being substantially continuous with those of the first and second housing elements whereby to provide support for

5
said fibers at the point where the second line chain receives the fibers from the first mentioned line chain.
